UNITED STATES PATENT OFFICE.

JAMES E. ROWE, OF PAWTUCKET, RHODE ISLAND, ASSIGNOR TO THE
E. JENCKES MANUFACTURING COMPANY, OF PAWTUCKET, RHODE
ISLAND, A CORPORATION OF RHODE ISLAND.

KNITTING-MACHINE.

SPECIFICATION forming part of Letters Patent No. 765,043, dated July 12, 1904.

Original application filed November 20, 1895, Serial No. 569,583. Divided and this application filed April 4, 1896. Serial No. 586,152. (No model.)

To all whom it may concern:

Be it known that I, JAMES E. ROWE, of the city of Pawtucket, county of Providence, in the State of Rhode Island, have invented certain new and useful Improvements in Knitting-Machines; and I do hereby declare the following specification, taken in connection with the accompanying drawings, forming a part of the same, to be a full, clear, and exact description thereof.

The present application is a divisional case from my application, Serial No. 569,583, filed November 20, 1895, and the invention included herein relates more especially to an extra-thread mechanism for use in connection with knitting-machines which are used for knitting stockings.

In knitting-machines of the class referred to it is desirable to use an extra thread on the heel and toe; and it is the object of this invention to provide a mechanism which shall be simple in construction and positive and accurate in action for inserting and withdrawing said extra thread at the proper times.

To that end the invention consists of the features and combination hereinafter described and claimed.

In the drawings, Figures 1 and 2 are perspective views of one form of mechanism embodying the present improvements. Fig. 3 is a longitudinal sectional view through the hub K⁶. Fig. 4 is a perspective of a modified form of gripping-jaw.

A vertical rod K is secured in any suitable manner to the frame of the knitting-machine to which the extra-thread mechanism is applied. Secured to the rod K and extending over the knitting-head is an arm K⁵, provided at its outer end with a vertical boss or hub K⁶. Loosely mounted in the boss K⁶ is a tube k, provided at its lower end with gear-teeth forming a pinion k', and at its upper end with a projecting flange k⁴, which engages the end of the boss K⁶ and supports the tube k. A pin k², provided with a V-shaped slot in one side, with the point of the V at the axis of the

pin, is secured inside the tube k and forms a guide for the thread. Secured in the tube below the pin k² is a plug k³, provided with a hole through which the thread passes. Loosely mounted on the tube k is a cap or thread-carrier k⁵, provided at its lower end with a flange k⁶, which rests on the flange k⁴, and at its top with a radial slot k⁷, having an offset portion k⁸ at its outer end for engaging the extra thread. The cap k⁵ also has a slot k⁹ in its periphery for a purpose to be described. The cap is held in place on the tube by a ring k¹⁰, secured to the arm K⁵. The sleeve k is rotated at the proper time by the segmental gear L', secured to a rock-shaft L and engaging pinion k'. The rock-shaft L is mounted in suitable bearings in the arm K⁵, and is operated at the proper times, as hereinafter described, by any suitable mechanism. (Not shown.)

Secured to the rock-shaft L above the arm K⁵ is an arm l, connected, by means of the link l', to a lever l², pivoted at l¹⁰ to an arm l¹. The arm l¹ carries at its free end a stationary gripper-jaw l¹, a pivoted gripper-jaw l², and a thread-guide l³. Secured to the pivoted jaw l² is an arm l³, provided at its free end with a slot which is engaged by a pin l⁴ on the end of the lever l². The pivoted jaw is also provided with a blade l⁵, which coacts with the lower edge of the stationary jaw in severing the thread. The arm l¹ is pivoted on a stud l⁶, secured to the arm K⁵, and is prevented from easy rotation by the friction-washer l⁷, forced against its upper face by the spring l⁸.

The operation of the mechanism is as follows: During rotary knitting the parts are in the position shown in Fig. 1 and the extra thread passes through the guides l¹⁴ l¹² and through the slot k⁷ in the cap k⁵ and has its end held between the jaws l¹ l². When the knitting-machine is changed from rotary to reciprocating knitting to knit the heel or toe, the shaft L is rocked and the parts are moved into the position shown in Fig. 2. The first

movement of the shaft L swings the lever l^2 on its pivot, thus opening the gripper-jaw l^5 and releasing the end of the extra thread, and continued movement of the shaft L brings the lever l^2 into engagement with a lug l^8 on the arm l^7 and forces said arm into the position shown in Fig. 2, with the open gripper-jaws projecting into the cap k^5 through the slot in its periphery and on each side of the extra thread. During this movement of the arm l^7 the guide l^{12} has given up the slack held between the guide l^{14} and the slot k^7 . Meanwhile the segment L' has turned the tube k one or more revolutions, and this motion has been transmitted to the cap k^5 by means of friction on spring k^{10} , secured to the flange k^6 and bearing against flange k^5 . As the cap revolves the end of the slot k^7 carries the extra thread into engagement with and wraps it around the main thread, and the two threads pass to the needles together, the extra thread being free to be drawn along by its engagement with the main thread by reason of the slack given up by guide l^{12} . It will be noted that the extra thread passes beneath the main thread in the V-shaped groove of pin k^2 and that thus the feed of the extra thread is insured. When the knitting-machine is changed from reciprocating to rotary knitting, the rod 30 L is returned to the position shown in Fig. 1. This movement of the rod and segment L' does not move the cap k^5 , as it is held from rotation by the pawl k^{11} , which engages a notch in the flange k^6 . This reverse movement of the rod 35 L first swings the lever l^2 on its pivot, thus closing the jaw l^5 to sever and grip the extra thread. After the jaws l^4 l^5 are closed, further movement of the lever l^2 carries the arm l^7 and the parts carried thereby into the position shown in Fig. 1, the jaws l^4 l^5 and the guide l^{12} drawing off thread from the extra thread-bobbin.

In Fig. 4 is shown a modified and preferred form of gripper-jaw. In this form the active face of jaw l^4 is provided with a groove l^{16} , and a spring l^{15} is secured to said jaw and normally projects beyond said active face, but is forced into the groove by the action of the jaw l^5 in gripping the thread. As the jaw l^5 closes, the thread is first held with a yielding pressure between the spring l^{15} and said jaw, then severed, and finally firmly held between the jaws l^4 l^5 . It will thus be seen that there is no liability that the end of the thread will escape from between the jaws after its severance and before the jaws are fully closed. The auxiliary yielding gripper-face may be applied to either the jaw l^4 or to the jaw l^5 , and the blade l^6 may be carried by either jaw. 55 With the construction above described it will be seen that the extra thread is carried into engagement with and wound one or more times about the main thread, and thus its accurate insertion insured, and that said extra

thread is held out of engagement with the main thread after its withdrawal and until it is to be again inserted.

What I claim as my invention, and desire to secure by Letters Patent, is—

1. In an extra-thread mechanism, the combination with a guide for the main thread, of a thread-holder for the extra thread, and means for moving said thread-holder to and from the main thread, a thread-engaging device and means for moving said thread-engaging device around the main thread, substantially as described. 70

2. In an extra-thread mechanism, the combination with a guide for the main thread, a gripper for gripping the extra thread, means for moving said gripper toward and away from the main thread, a thread-engaging device, and means for rotating said thread-engaging device around the main thread, substantially as described. 80

3. In an extra-thread mechanism, the combination with a guide for the main thread, a combined cutter and gripper for severing and gripping the extra thread, a thread-engaging device and means for rotating said thread-engaging device around said main thread, substantially as described. 90

4. In an extra-thread mechanism, the combination with an oscillating tube provided with a passage at its axis, of a cap at the end of said tube and frictionally engaging the same, a radial slot in the end of the cap, and means for preventing the rotation of the cap in one direction, substantially as described. 95

5. In an extra-thread mechanism, the combination with a guide for the main thread, a rotary carrier for the extra thread, a holder for the extra thread, means for moving said holder to draw off and give up slack thread, and means for severing the extra thread, substantially as described. 100

6. In an extra-thread mechanism, a combined cutter and gripper consisting of two co-acting gripping-jaws provided with cutting edges, one of said jaws being provided with an auxiliary yielding gripping-face, substantially as described. 110

7. In an extra-thread mechanism, a gripper consisting of a stationary gripper-jaw, a groove therein, a spring projecting from said groove, but adapted to be forced back therein, and a movable gripper-jaw, substantially as described. 115

8. An extra-thread mechanism, comprising a longitudinal guide for the main thread, an arm carrying a gripper, means for opening and closing the gripper and swinging the arm substantially at right angles to the said guide and means for severing the extra thread, substantially as described. 120

9. An extra-thread mechanism, comprising a longitudinal guide for the main thread, a combined cutter and gripper, consisting of

two jaws provided with cutting edges, and means for moving said cutter and gripper substantially at right angles to said guide, substantially as described.

5 10. In an extra-thread mechanism, the combination with a pivoted arm carrying a stationary gripping-jaw of a jaw pivoted to said arm, a lever pivoted to said arm and engag-

ing said jaw, a rock-arm connected to said lever, a projection on said arm in the path of said lever, and means for rocking said rock-arm, substantially as described.
